UNITED STATES PATENT OFFICE.

FRANKLIN M. KLEINE, OF MINNEAPOLIS, MINNESOTA.

WRENCH.

1,309,860.

Specification of Letters Patent. Patented July 15, 1919.

Application filed October 28, 1918. Serial No. 259,995.

To all whom it may concern:

Be it known that I, FRANKLIN M. KLEINE, a citizen of the United States, residing at Minneapolis, in the county of Hennepin and State of Minnesota, have invented certain new and useful Improvements in Wrenches, of which the following is a specification, reference being had to the accompanying drawings.

10 This invention relates to wrenches, and has for its primary object to provide a durably constructed wrench of the quick adjustable type, the several parts of which are of relatively simple form so that the wrench 15 in its entirety may be manufactured and sold at small cost.

It is another and more particular object of the invention to provide a wrench of the above type having a body or frame, a rotatable adjusting member mounted in said frame, said frame having a fixed jaw at one end, and complementary jaws slidably mounted upon the frame, with which said adjusting member is operatively engaged.

25 With the above and other objects in view, the invention consists in the improved construction, combination and relative arrangement of the several parts as will be herein-after more fully described, subsequently 30 claimed and illustrated in the accompanying drawing in which similar reference characters designate corresponding parts throughout the several views, and wherein:—

Figure 1 is a side elevation illustrating the preferred embodiment of my invention;

Fig. 2 is a section taken on the line 2—2 of Fig. 1; and

Fig. 3 is a perspective view of the wrench frame or body.

40 Referring to the drawings 5 designates the body of the wrench having an obliquely extending jaw 6 formed on one of its ends. The other end of the body is provided with a pair of arms 7 and 8 arranged in parallelism and spaced, and formed through the body is a cylindrical bore 9. This bore 9 connects the cone chamber or cavity 10 and the crotch 7a of the space between said arms.

45 The wrench body 5 has an obliquely extending face 11, and at each edge of this face, a guide rib 12 is formed upon the body of the wrench. 13 designates an adjustable jaw which is disposed in confronting relation to the jaw 6, and is provided upon one 55 end with parallel channels or grooves, indicated at 14, to receive the guide ribs 12.

This end face of the jaw 13 is also formed with a series of threads or teeth 15.

A knurled or roughened cylinder is mounted in the space between the arms 7 and 8, and one end of this cylinder is provided with an extension rod 16, which rotatably extends through the bore 9. The other end of the cylinder is provided with a reduced terminal lug or stud 19, which rotatably 60 engages a socket formed centrally in a cap 20. By this construction it will be seen that the cylinder may freely rotate, and without excessive binding, and also may be rotated any time while the hand of the operator is 65 in engagement with the body of the wrench. The reduced rod at one end of the cylinder protrudes into the cone chamber, and on its terminal a cone gear 17 is fixed. The teeth of this cone gear mesh with the teeth 15 70 of the slideable jaw 13, so that when the cylinder is rotated in either direction, the slideable or movable jaw may be operated toward and from the fixed jaw. This cap member extends across the open end of the 75 slot 8 and is suitably secured to the end of the body or frame 5. It will thus be seen that by merely rotating the rod 16 with the fingers of the hand grasping the wrench, the jaw 13 can be very easily and quickly 80 adjusted toward or from the fixed jaw 6 and disposed in proper spaced relation thereto for engagement with an object. I have herein shown the cone-gear 17 detachably secured to the end of the rod 16, though it 85 will, of course, be understood that, if desired, these parts can be integrally formed.

From the foregoing description, taken in connection with the accompanying drawing, the construction, manner of operation and 90 several advantages of the device will be clearly and fully understood. The article is of great convenience and serviceability in practical use, and may be roughly handled without getting out of order. The device 100 is also well adapted for use in places which are not easily accessible, as the movable wrench jaw can be readily adjusted by the fingers of the hand grasping the wrench. The several elements of my improved 105 wrench are also strong and durable, and they can be very easily and quickly assembled or disassembled when necessary. The wrench may, of course, be constructed in various sizes, and in view of its simplicity it will be 110 appreciated that the manufacturing cost thereof will be relatively small.

While I have herein shown and described the preferred construction and arrangement of the various parts, the device is nevertheless obviously susceptible of considerable modification therein and I, accordingly, reserve the privilege of adopting all such legitimate changes as may be fairly embodied within the spirit and scope of the invention as claimed.

10 I claim:—

1. In a wrench, the combination with a one-piece body having a fixed jaw at one end and a cone-shaped chamber between the body and the jaw, said chamber being open adjacent the opposite faces of the body, said jaw having an inclined dovetailed base in parallelism with one of the inclined edges of the chamber, of a movable jaw having dove-tail connections with the dove-tailed face, the other end of the body having a pair of spaced arms, thereby causing a crotch to be formed at one end of the space between the arms adjacent the end of the body, said body having a bore extending from the crotch between the arms and in communication with the chamber, a knurled cylinder mounted between the arms and having a rod at one end passing through the bore, a cone worm in said chamber and fixed to the end of said rod and having a meshing engagement with the dove-tailed part of the movable jaw, the other end of the cylinder having a projection, and a cap connected to the

ends of the arms and being engaged by said projection, whereby the cylinder is capable 35 of freely rotating, to operate the worm to actuate the movable jaw.

2. In a wrench, the combination with a one-piece body having a fixed jaw at one end, and a pair of spaced arms at its opposite end, thereby causing a crotch to be formed at one end of the space between the arms and adjacent the end of the body, a cone-shaped chamber between the body and the fixed jaw, of a movable jaw having sliding connections with one of the faces of the fixed jaw, a bore connecting the crotch between the arms and the chamber, a knurled cylinder body movably mounted between the arms and having a rod extension passing through the bore and protruding into the chamber, the other end of the cylinder having a projection, a cone worm on the projecting end of the rod and mounted in the chamber, and having a meshing engagement 45 with a part of the movable jaw, and a cap detachably fixed to the ends of the arms and receiving said projection, whereby the cylinder may be rotated freely and without binding.

60 In testimony whereof I hereunto affix my signature in the presence of two witnesses.

FRANKLIN M. KLEINE.
